UNITED STATES PATENT OFFICE.

JOSEPH W. SCHLOSS, OF NEW YORK, N. Y.

DESIGN FOR DRESS-TRIMMING.

SPECIFICATION forming part of Design No. 22,048, dated December 6, 1892.

Application filed October 31, 1892. Serial No. 450,560. Term of patent 3½ years.

To all whom it may concern:

Be it known that I, JOSEPH W. SCHLOSS, a citizen of the United States, residing at New York, in the county of New York and State of New York, have invented a certain new and original Design for Dress-Trimmings, of which the following is a full, clear, and exact description.

My new and original design relates to braids for dress-trimmings, and is illustrated in the accompanying drawing.

It consists of a central smooth braid or band like figure *a*, which is crossed at right angles by cords *b*, which cords pass in pairs alternately in front of and behind the band *a*. The cords are separated by spaces *b'* and at the edges of the trimming are bent into double concentric loops *b²* *b³*. The smaller of these loops on one edge of the trimming is formed by the pairs of cords which pass behind the band *a*, while the smaller loops on the other edge of the trimming are formed by the pairs of cords which pass in front of the band *a*.

This makes the loops on the opposite edges occur alternately instead of opposite each other. Just inside of the base of the loops on each edge is arranged a flat cord or band *c*, somewhat narrower than the middle band *a*. These edge bands are crossed by the transverse cords *b* in the same manner that the said cords cross the band *a*.

d, e, and f and d', e', and f' represent rows of stitching or threads which are looped around each of the cords *b*. One of these rows is arranged on each side of the band *a* and one on each side of each of the bands *c c*.

I claim—

The design for dress-trimmings herein described and illustrated.

In testimony whereof I subscribe my signature in presence of two witnesses.

JOSEPH W. SCHLOSS.
